NOZZLE FOR SPRAYERS

Henry E. Brandt, North St. Paul, Minn., assignor
to The Dobbins Manufacturing Company,
North St. Paul, Minn., a corporation of Minne-
sota

Application August 2, 1934, Serial No. 738,085

3 Claims. (Cl. 299—89)

This invention relates to a sprayer such as is used to spray insecticides and other liquids, and particularly to a novel structure of nozzle for such a sprayer.

5 In the sprayer of the type used the liquid is sprayed by means of compressed air and it is desirable to have the liquid and air thoroughly mixed to finely divide the liquid and so that the same can be sprayed from a discharge passage 10 in a flaring body or stream.

It is an object of this invention, therefore, to provide a simple and efficient structure of sprayer nozzle comprising few parts and having means for finely dividing and mixing the air and liquid 15 and efficiently discharging the same.

It is a further object of the invention to provide a nozzle structure comprising a nozzle member having a chamber therein with a discharge passage leading therefrom together with means 20 for delivering air tangentially into said chamber from about the sides thereof and means for delivering liquid centrally to said chamber whereby the air and liquid are given a whirling motion in said chamber and the liquid is sprayed in finely 25 divided condition.

It is still another object of the invention to provide a nozzle structure comprising a nozzle member having a longitudinal passage therethrough, a tube for supplying liquid under pressure extending through said passage and forming an annular chamber therein, a cap removably secured to said member having a chamber therein with a discharge passage leading therefrom, said cap holding said tube in place and having passages leading to said chamber from said annular passage for causing a whirling movement of air and liquid in said chamber, said tube being readily removable when said cap is removed.

These and other objects and advantages of the 40 invention will be fully set forth in the following description made in connection with the accompanying drawing, in which like reference characters refer to similar parts throughout the several views and in which:—

45 Fig. 1 is a view partly in side elevation of a sprayer of the type used, some parts being shown in vertical section;

Fig. 2 is a partial vertical longitudinal section of the device;

50 Fig. 3 is a vertical section taken on line 3—3 of Fig. 2 as indicated by the arrows;

Fig. 4 is a vertical section taken on line 4—4 of Fig. 2 as indicated by the arrows; and

55 Fig. 5 is a partial view in side elevation with some parts removed.

Referring to the drawing, a sprayer is shown comprising a liquid container 10. While this container may take various shapes, in the embodiment of the invention illustrated it is shown as of cylindrical shape. Said container 10 has secured thereto and set somewhat thereinto a cylindrical member 11, the same forming a pump cylinder and having reciprocable therein a cup plunger 12 of leather or similar flexible material secured by a nut 13 to a plunger rod 14 extending through the end 11a of said cylinder and having a handle 15 secured thereto at its outer end. Said rod 14 also preferably has secured thereon in any suitable manner, as by welding, a stop collar 16. End member 11a is shown as threaded onto cylinder 11. Cylinder 11 has a partition 11b extending thereacross adjacent one end, the same having an aperture 11c therethrough normally closed by a check or flexible valve 17. While different types of valves might be used, in the embodiment of the invention illustrated valve 17 is shown as a sheet of flexible material such as leather, secured to partition 11b at one side of opening 11c by a headed rivet 18. Cylinder 11 beyond partition 11b, and container 10 at the top 20 thereof have registering openings 10a. Cylinder 11 has a frusto-conical portion 11d at its end opposite member 11a and a nozzle member 19 is secured in an opening in the end of said portion 11d. Member 19 can be secured in any suitable manner as by welding or soldering. Member 19 has a longitudinal passage 19a extending centrally therethrough and the same has a plurality of radial slots 19b extending outwardly to its periphery from passage 19a at the outer end 35 thereof. A tube 20 is provided, the same having a flange 20a at one end engaging the outer end of member 19 and the same extends through passage 19a into cylinder 11 and then downwardly through openings 10a into container 10, the lower 40 open end of said tube being disposed adjacent the bottom of container 10. A pair of holes 20b are formed in tube 20 adjacent flange 20a, affording communication between the interior of said tube and the annular passage about tube 20. A cap 21 is interiorly bored and threaded to be screwed onto the threaded periphery of member 19 and the end wall of the bore in cap 21 engages the outer side of flange 20a holding the same firmly against the end of member 19. Cap 21 has 45 a chamber 21a therein shown as centrally disposed and communicating with the passage through tube 20. Said cap also has a small discharge aperture or passage 21b disposed centrally thereof and leading from chamber 21a. Said 50 55

cap also has a plurality of passages **21c** extending outwardly from passage **21a**, the same being arranged tangentially as shown in Fig. 4. The passages **21c** communicate at their outer ends with the passages **19b** with which they are in longitudinal alignment. When the cap **21** is removed the tube **20** can be withdrawn through member **19** and removed as indicated in Fig. 5.

In operation, the liquid to be sprayed is placed in container **10**. The handle **15** is reciprocated and air is pumped in cylinder **11** and forced through the opening **11c** in partition **11b**. Valve **17** prevents the passage of air back through opening **11c** so that compressed air is contained in cylinder **11** beyond partition **11b** and on top of the liquid in container **10**. Liquid is forced upward through tube **20** and passes from the end of said tube into chamber **21a**. Compressed air at the same time is forced through passage **19a** around said tube and this air passes through slots **19b** around the edge of flange **20a** into the passages **21c** and enters chamber **21a**. The tangential jets of air passing into chamber **21a** cause a whirling motion in said chamber and the air and liquid passes out through discharge passage **21b** in the shape of a cone, the liquid being finely divided. The liquid and air are thoroughly mixed in chamber **21a** and the liquid divided into fine particles. Some air also enters tube **20** through openings **20b** and this also assists in the disintegration and discharge of said liquid. The action of the nozzle has been found to be a great improvement upon prior structures used. As already stated tube **20** can be readily removed when cap **21** is removed.

From the above description it is seen that applicant has provided a very simple and efficient form of sprayer nozzle. The parts of the nozzle are quite few in number and the same are easily made and assembled. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

1. A sprayer structure having in combination,

a nozzle member having a longitudinal passage therethrough, a liquid supplying tube extending through said passage and forming an annular passage about said tube, a second member secured to said nozzle member having a substantially cylindrical chamber therein at the end of said tube, said tube having an opening at its end for discharging into said chamber said member having a discharge aperture of much smaller diameter than said opening leading from said chamber, a plurality of passages in said structure leading to said chamber and tangentially arranged relatively thereto, means connecting said last mentioned passages and said annular passage, means for supplying liquid under pressure to said tube and air under pressure to said annular passage whereby said air and liquid are delivered to said chamber and given a whirling motion therein.

2. A sprayer structure having in combination, a nozzle member having a longitudinal passage therethrough, a tube for receiving liquid under pressure extending through said passage and forming an annular chamber about said tube, said tube having a flange engaging the end of said nozzle member, a cap threaded on said nozzle member and engaging said flange having a small discharge aperture and having a substantially cylindrical chamber therein outwardly of said flange communicating with said tube, said tube having an open end discharging centrally into said chamber, a plurality of passages leading outwardly from said chamber and tangentially arranged relatively thereto, means connecting said last mentioned passages and said annular passage, and an opening in said tube communicating with said annular passage.

3. A sprayer nozzle having in combination, a member having a substantially cylindrical chamber therein with a discharge passage of very much smaller diameter than said chamber leading from said chamber, a tube having an open end for delivering liquid under pressure centrally to said chamber, means for delivering air under pressure tangentially to said chamber beyond said tube whereby said liquid and air are mixed and give a whirling motion in said chamber and projected through said passage and means for delivering air to said tube a short distance from said chamber to preliminarily break up said liquid.
